CLAIM

The ornamental design for a fabric construction, as shown and described.

DESCRIPTION

FIG. 1 is a top plan view of a fabric construction embodying our design;

FIG. 2 is a bottom plan view thereof;

FIG. 3 is a front end elevational view thereof;

FIG. 4 is a rear end elevational view thereof;

FIG. 5 is a right end elevational view thereof; and,

FIG. 6 is a left end elevational view thereof.
